Fig. 1

Fig. 2

Fig. 3

Fig. 5

FIG. 1 is a front perspective view of a desk name plate or the like showing my new design:

FIG. 2 is a front elevational view;

FIG. 3 is a rear elevational view;

FIG. 4 is a top plan view;

FIG. 5 is an end view.

The stippling indicates a color different from that of the wooden body of the name plate and different from the parallel recessed stripe beneath the stippled area.

The broken line representation of indicia in FIG. 1 is for purposes of illustration only.

I claim:

The ornamental design for a desk name plate or the like, substantially as shown and described.
